METHOD FOR CONCENTRATING AND SEPARATING THE COMPONENTS OF GASEOUS MIXTURES

Edoardo Mazza, Turin, Italy

Application April 28, 1934, Serial No. 722,997
In Italy May 5, 1933

1 Claim. (Cl. 183—115)

This invention relates to a method for concentrating and separating the components of gaseous mixtures, characterized chiefly by the fact that, for the purpose of more efficiently separating the various gases or vapours constituting the mixture, the combined action of centrifugal force, gravitation and molecular velocities of the gases or vapours is used. In this way a stratification both in radial and axial direction is produced in the mixture so that the various components may be separated and conveyed to different places.

An important feature of this invention consists in the fact that the mixture is constantly maintained in dynamic balance during the concentration and separation of the components of the mixture. The concentration may be intensified by causing the gaseous mass under treatment to pass successively through different conditions of dynamic balance, for instance by varying the general composition of the mixture by successively subtracting parts of the mixture of already modified composition, so that new conditions of dynamic balance are generated and the action of the centrifugal force is gradually varied.

This invention has further for its object a simple, efficient and compact apparatus for carrying out the above described method.

Said apparatus is substantially constituted by a drum rotating on a vertical axis and comprising an annular chamber concentric to the drum axis divided into compartments by means of radial partitions conveniently curved in the way of impeller blades. Each of these compartments is in communication with the interior of the drum through a supply opening in proximity to the concave face of the partitions and with the atmosphere through two delivery openings, the lower one of which is provided between the two partitions and the upper one in proximity to the convex face of the partitions. A partition (classifying device) is arranged between the delivery openings and extends from the edge of the inner opening to the wall of the outer cylinder. Said partition is provided with passages for the separated components placing into communication the supply section with the delivery section of each compartment; the distance of said passages from the center increasing from the supply towards the delivery end.

By this arrangement the mixture of gases or vapours is impinged by the centrifugal force on the outer wall of the drum and its components

are separated in layers according to their specific gravity, the specific gravity of the layers increasing from the center towards the periphery. Owing to the different molecular velocities of the components and to the suction produced by the rotation in the delivery section, the lighter gases or vapours (owing also to the movement of the mixture with respect to the drum) pass through the passages. A classification of the components is thus obtained: the heavier components are collected at the periphery of the supply section where they descend by gravity and are discharged to the outside through an opening provided near the bottom, while the lighter components are collected in the upper part of the supply section and are conveyed by suction through the passages into the delivery section and are subsequently discharged to the outside through the upper opening.

By suitably controlling the speed of rotation of the drum according to the specific gravity of the components of the mixture, it will be possible to separate all components of the mixture by passing this latter several times through the classifier. Or the delivery section may be subdivided by means of suitably arranged partitions in as many chambers as there are passages for the separated components; said chambers may communicate with the outside at different places, so that it will be possible to collect separately the various components of the mixture or obtain concentration of said components.

The annexed drawing shows by way of example a constructional form of the classifier according to this invention.

Fig. 1 is an axial section of the apparatus. The upper half of Fig. 2 shows a section on line A—A of Fig. 1 and the lower half a section on line B—B of Fig. 1.

Referring to the drawing, 1 is a container in which is rotatably mounted on a vertical axis a classifying drum constituted by a bottom 2, a cover 3, an outer cylindrical wall 4 and an inner cylindrical wall 5. All these parts are mounted on a vertical shaft 6 supported by a bearing 7 and form an annular chamber, subdivided in a circular set of compartments by means of partitions 8 in the form of blades. Each of these compartments is concentric to the axis of the drum and communicates with a supply chamber 9 enclosed by the inner wall 5 through openings 10 provided in said wall in proximity to the concave face of each of the partitions forming the compartment and with the inside of the con-

tainer 1 through an opening 12 in proximity to the bottom 2 and an opening 11 in proximity to the cover 3 and to the convex face of the other partition 8 forming the compartment.

5 The delivery openings 11 and 12 for the concentrated gases are provided on the wall edges and are of the lowest possible width in the direction parallel to the axis of rotation while their width in the direction perpendicular to said axis 10 is sufficient to permit the full discharge of the concentrated gases without creating highly objectionable counter pressures.

15 It has been found that the highest efficiency is obtained by reducing the edge of said openings to the lowest possible thickness allowed by the strength of the material.

20 In each compartment is mounted, parallel to the axis of rotation, a row of columns 13 extending from the edge of the opening 10 opposite to the adjacent partition 8, to a point of the outer wall between the openings 11 and 12. Said columns are so shaped as to form staggered passages 14 arranged at increasing distances from the axis of rotation each being formed by 25 an inner radial part a and an outer flared part b constituting a guide for the fluid threads flowing in the compartment.

25 The passages 14 place the supply section 15 in communication with the delivery section 16.

30 The supply chamber 9 projects from the container 1 and ends in an enlarged part having the form of a plate 17 carrying the suction and force blades 18 keyed to the shaft 6.

35 The container 1 is subdivided in two superposed chambers 19 and 20 separated from each other by an annular horizontal partition 21 secured to the container wall and loosely embracing a ring 25 fixed to the wall 4 in order to form with the assistance of the centrifugal 40 force a fluid tight seal between the compartments 19 and 20 and to reduce the bending moments of the rotating parts. The delivery sections 16 communicate through the openings 11 with the chamber 19 provided with a discharge nipple 22 and the supply sections 15 communicate with the chamber 20 provided with a discharge nipple 23 through the openings 12. When more than two components of the mixture are to be obtained the number of rings 25, 45 partitions 21 and chambers should be increased accordingly.

50 The center of gravity should coincide with the intersection of the axis of rotation with the support plane of said rotating mass in order that the gyroscopic action of the rotating mass (constituted by the classifying rotating drum, plate 17 and blades 18) be of full efficiency; therefore the shaft 6 extends under the bearing 7 and at its lower end is keyed a fly-wheel 24 of sufficient weight.

55 The apparatus works as follows:

60 The opening of the plate 17 is placed in communication with the chamber containing the gaseous mixture to be separated in its components, the separating rotating drum is set into rotation. The blades 18 effect the suction of the mixture and press and convey this latter into the supply chamber, from which through

the openings 10 it is distributed to the supply sections 15 of the various compartments.

65 In these sections the mixture falls under the action of the blade partitions 8 and is set in rotation; the centrifugal force impinges the components of heavier specific gravity on the outer wall thus producing an annular concentric stratification, the density of which increases from the centre towards the periphery. These layers, owing to the presence of the blades 18, 10 move forward in the sections 15 and are brought to the openings b of the separating passages 14. When the inner lighter layers reach said openings b, owing to their higher molecular velocity 15 in comparison with the heavier layers and to the suction produced by the rotation of the drum in the sections 16 through the openings 11 against the opposing action of the centrifugal force, they pass centripetally through the passages 14 and are conveyed into the sections 16 20 of the compartments. The components of higher specific gravity left in the sections 15, fall by gravity on the bottom and are discharged through the openings 12 in the chamber 20 of the container, from which they may be collected 25 through conduits connected to the nipple 23. The components of lighter specific gravity are conveyed through the openings 11 into the chamber 19, from which they may be discharged 30 through a nipple 22.

35 If there is a substantial difference in the specific gravity of the mixture components it will be possible to effect the separation in a single cycle; if on the contrary said difference is small, a concentration of the components will be obtained in the first cycle and the operation will be repeated and by controlling the speed of rotation of the rotating separating drum, during the cycles, a substantially complete separation of the various mixture components will be obtained in a few cycles.

40 It is evident that this method and apparatus for concentrating and separating gaseous mixtures may be combined wholly or in part with other concentration and separation processes 45 used for the treatment of gaseous mixtures.

45 What I claim is:

50 The method of concentrating and separating the constituents of a gaseous mixture consisting in dividing a gaseous stream into a plurality of generally segmental gaseous masses, rotating said masses about a common vertical axis thereby forming strata of progressively increasing specific gravity from the axis of rotation, withdrawing portions of the lighter constituents in 55 a centripetal direction from each of said segmental gaseous masses along a plurality of restricted circumferentially spaced and substantially radial paths, progressively more remote from the axis of rotation and separately withdrawing heavier constituents from the lower portion and lighter constituents from the upper portion of each of the masses whereby centrifugal force, gravity and the difference in the molecular velocities of the constituents are utilized to 60 concentrate the mixture into fractions enriched in lighter and heavier constituents.
